(57) **CLAIM**

The ornamental design for the bowl with embedded challenge coin, as shown and described.

DESCRIPTION

FIG. 1 is a perspective front right side view of a bowl with embedded challenge coin.

FIG. 2 is a right side view of the bowl with embedded challenge coin.

FIG. 3 is a left side view of the bowl with embedded challenge coin.

FIG. 4 is a front side view of the bowl with embedded challenge coin.

FIG. 5 is a back side view of the bowl with embedded challenge coin.

FIG. 6 is a top view of the bowl with embedded challenge coin; and,

FIG. 7 is a bottom view of the bowl with embedded challenge coin.

The broken lines show portions of the bowl with embedded challenge coin that form no part of the claimed design.

1 Claim, 7 Drawing Sheets
